U.S. Cl. D9—219

Fig.1.

Fig.2.

Fig.3.

FIG. 1 is a top plan view of a packaging tray for cans or the like showing my new design, it being understood that the ornamentation seen in the upper left of FIG. 1 is continuous over the entire top surface of the tray bottom;

FIG. 2 is a side elevational view partially in section taken on the line 2—2 of FIG. 1; and

FIG. 3 is an end elevational view.

I claim:

The ornamental design for a packaging tray for cans or the like, as shown and described.
